UNITED STATES PATENT OFFICE.

JORDAN L. MOTT, OF MOTT HAVEN, NEW YORK.

DESIGN FOR BATH-TUBS.

Specification forming part of Design No. 7,106, dated January 13, 1874; application filed December 29, 1873.
[Term of Patent 7 years.]

To all whom it may concern:

Be it known that I, JORDAN L. MOTT, of Mott Haven, in the county of Westchester, and State of New York, have invented a Design for a Bath-Tub, of which the following is a specification:

The said design for a bath-tub which I have devised is fully represented in the accompanying print of a wood-cut, to which reference is made. The said design consists of the oval or rounded form for the corners A at the ends; also the bottom, side, and end horizontal corners B.

I claim as my invention—

The design for a bath-tub, as shown and set forth.

JORDAN L. MOTT.
